UNITED STATES PATENT OFFICE.

FERDINAND GUNDORPH, OF PORTLAND, OREGON.

PIN-JEWEL HOLDER.

SPECIFICATION forming part of Letters Patent No. 252,660, dated January 24, 1882.

Application filed November 23, 1881. (Model.)

To all whom it may concern:

Be it known that I, FERDINAND GUNDORPH, of Portland, in the county of Multnomah, in the State of Oregon, have invented an improvement for a pin-jewel holder for setting the ruby-pin in the roller or disk on the shaft of the balance-wheel in watches, of which the following is a specification.

The nature or object of my invention is to secure a means of setting a ruby-pin in a balance-disk in a more perfect manner than hitherto, so that the said pin shall be parallel to the axis of the balance-shaft, and the plane face of same perfectly tangent to the circle of oscillation of the balance.

In Figure 1 is shown a plan, as seen from the top, and to the left an enlarged, view of the central part with pin, &c. In Fig. 2 is shown a section of the same parts, and Fig. 3 shows a plan of the under side of the above. The plans are about twice as large as the tool.

In setting a ruby-pin in the ordinary manner it is difficult to keep the parts true and square; but by the device shown it is possible to set the pin true at all times and with certainty. The pin *d*, having a flat side placed against the squared end of sliding piece *b*, operated by a spring, *h*, is pressed against two points, *e*, also true and square, (as regards lines,) *b* and *e* forming, as it were, jaws of a vice, clamped to-

gether by the spring *h*. The balance-disk for setting the pin in is laid on the portion around the center, and the end of the balance-shaft placed in the slot *f*, where it may pass downward and out of the way. The hole in the edge 35 of the disk for the pin-setting is placed loosely over the pin, and a small grain of gum-shellac placed against it for fusion. The whole is now placed in the flame of a spirit-lamp, and when the spring-thermometer *g* shows the proper 40 point of heat on the indicator *i* the whole is removed and allowed to cool, *i* being so graduated that the melting-point is always accurately shown. *g* is composed of two metals causing the expansion, as above. *g* and *h* are fastened 45 to the face plate *k* by screws, as also is *k* to *j*. Two little pins, *c*, are on either side of the spring *h* for moving the clamp-piece *b* back and forth by the end *a* in the fingers. This end *a* is turned under the edge of the face-plate *k* in 50 such a way as to prevent its becoming disengaged or out of place.

I claim—

A pin-jewel holder consisting of the parts *a* *b* *c* *d* *e* *f* *g* *h* *i* *j* as a whole and in combination, 55 as described, and for the purpose set forth.

FERDINAND GUNDORPH.
